ANIMATED DECORATIVE LAMP

Aubrey B. Leech, Los Angeles, Calif., assignor to Econolite Corporation, Los Angeles, Calif., a corporation of California

Application September 8, 1952, Serial No. 21,379

Term of patent 7 years

(Cl. D48—20)

To all whom it may concern:

Be it known that I, Aubrey B. Leech, a citizen of the United States of America, residing in the city of Los Angeles, county of Los Angeles, and State of California, have invented a new, original, and ornamental Design for an Animated Decorative Lamp, of which the following is a specification, reference being had to the accompanying drawing forming a part hereof.

The dominant features of my design are shown in solid lines.

I claim:

The ornamental design for an animated decorative lamp, substantially as shown and described.

AUBREY B. LEECH.
